SERVING TRAY

William J. Devitt, New York, N. Y., assignor to Identafray Corporation, New York, N. Y., a corporation of New York

Application October 12, 1949, Serial No. 5,441

Term of patent 14 years

(Cl. D44—10)

To all whom it may concern:

Be it known that I, William J. Devitt, a citizen of the United States of America, residing at New York, in the county of New York and State of New York, have invented a new, original, and ornamental Design for Serving Tray, of which the following is a specification, reference being made to the accompanying drawing, forming a part thereof, in which:

Fig. 1 is a perspective view of a serving tray embodying the design in accordance with the invention; and

Fig. 2 is a cross-sectional elevational view of said serving tray taken through line 2—2 of Fig. 1.

I claim:

The ornamental design for a serving tray, substantially as shown.

WILLIAM J. DEVITT.
